Richard J. Cook

ATTORNEY

UNITED STATES PATENT OFFICE.

CHARLES I. NELSON, OF MARYSVILLE, WASHINGTON, ASSIGNOR OF ONE-HALF TO
JAMES G. GROVES.

BROODER.

Application filed April 18, 1927. Serial No. 184,680.

This invention relates to improvements in brooders, and more particularly to brooders for baby chicks; the principal object of the invention being to provide an improved form 5 of heating system for brooders which permits an accurate temperature control within the brooder and provides for the raising and lowering of the heating element so as to bring it closer to or farther from the chicks 10 as is required for their comfort.

Another object of the invention is to provide a brooder heating system embodying an upper and a lower series of pipe coils through which water or steam, as the heating medium, 15 may be circulated and to connect these coils with a centrally located heater, or boiler, and to provide valves in the coils whereby the circulation of the heating medium may be controlled in such manner as to vary the heat 20 as needed and to direct it to the upper or lower part of the brooder as desired.

Another object of the invention is to connect the heating coils with the boiler by flexible pipe so as to permit the boiler to be raised 25 or lowered to bring it nearer to or farther from the chicks.

Other objects of the invention reside in the various details of construction and combination of parts as is hereinafter described.

In accomplishing these and other objects 30 of the invention, I have provided the improved details of construction, the preferred forms of which are illustrated in the accompanying drawings, wherein—

Figure 1 is a perspective view of a brooder 35 embodied by the present invention.

Figure 2 is a perspective view of the heating system, with the side and top walls and floor removed.

Figure 3 is a cross section of the brooder. 40 Referring more in detail to the drawings—

In the present device the heating coils constitute the frame structure from which the top and side walls of the brooder are supported. The coils are arranged in upper and lower units; the upper unit comprising a continuous pipe that forms a flat, horizontally disposed coil made up of the outer end parts 45 1 and 2 which form the opposite ends of the top frame, the parts 3 and 4 which form the 50 opposite sides of the frame, and the parts 5, 6, 7 and 8 which are parallel with, but spaced respectively within, the pipes 7, 3, 2 and 4. Located centrally of the coil is a heater, or 55 boiler, 10 in which water may be heated or

steam generated and this is connected at the top, by means of a flexible tube, or pipe, 11, with the end of the pipe 8 so that hot water or steam from the boiler may pass into the coil. There is also a supplemental heating 60 coil lying in the same plane of the upper coil just described, and this comprises parallel pipes 12 and 13 extending closely along opposite sides of the boiler and parallel with the side pipes of the main coil; the pipes 12 65 and 13 having ends connected by a cross pipe 14 and their other ends connected, respectively, with the pipes 5 and 6, and being provided near their connection with these pipes with cut-out valves 16 and 17 which are opened 70 when it is desired that circulation pass therethrough but which otherwise are closed. There is also provided a cut out valve 18 in the pipe 6 between the connections of the supplementary coil and the main coil, and this 75 may be closed when it is desired to cause the heating medium to pass also through the supplementary coil.

The lower heating unit comprises a horizontal coil of substantially the same dimensions as the upper coil and comprises opposite end pipes 20 and 21, opposite side pipes 22 and 23, and a pipe 24 which extends parallel within the pipe 23, from the end of the pipe 20 to adjacent the boiler and is then connected 80 to the base of the boiler by means of a flexible pipe, or tube, 25. The inlet end of the pipe 23 is connected by a vertical pipe 26 with the end of the pipe 1 of the upper unit which terminates directly above it. A connection 28 85 is also provided between the pipes 23 and 24 to permit the circulation of the heating medium to pass directly from the pipe 23 to the boiler instead of circling the coil, and a cut-out valve 30 is provided in this connection 90 and a similar valve 31 is provided in the pipe 23 just past the connection of the pipe 28; these valves may be opened and closed as required in order to cause the circulation of the medium to pass directly or circuitously 95 to the boiler.

With the two heating units so constructed and connected, water heated in the boiler 10 will flow from the top of the boiler through the pipes 11, 8, 7, 6, 5, 4, 2, 3 and 1, thence 100 downwardly through the pipe 26 and through pipes 23, 21, 22, 20, 24 and 25 to return to the boiler. If the valve 31 is closed and the valve 30 opened, the circulation will pass 105 from the pipe 23 into the boiler direct with- 110

out encircling the lower coil; also, if the valves 16 and 17 of the supplementary coil of the upper element are opened and the valve 18 is closed, the circulation will pass through 5 the pipes 12, 13 and 14, thus giving additional heating capacity.

The boiler 10 is of cylindrical form and is suspended by a bar 35 that extends vertically and centrally from the upper end of the 10 boiler and is slidably contained within an opening 36 in an upwardly bowed supporting bar 37 which rests, at its ends, on two bars 38 and 39 disposed transversely on top of the coils of the upper heating element. 15 The boiler may be adjusted vertically by means of this bar 35 and held at any adjusted position by engaging teeth 39, that are provided on the edge of the bar, with the edge of the notch 36; this adjustment being provided in order that the boiler may be moved 20 closer to or farther from the floor of the brooder as is desired to bring the heat closer to or farther from the chicks; also, for the purpose of controlling the rate of circulation 25 through the pipes.

The floor 40 of the brooder is formed, preferably, in sections, of wood and is laid just on top of the lower pipe coils and it is provided about its edges with inclined runways 41 which provide easy access of the chicks into and from the brooder. The top 30 45 of the brooder may be of canvas or other material and should be so constructed or sufficiently elevated to permit the boiler to be raised and lowered, and suitable openings are provided in the top through which the rod, or bar, 35 and the supporting bar 37 extend. The side walls of the brooder are preferably formed of canvas strips 48 that are 35 secured to the edges of the top and depend therefrom, preferably, about one-half way to the floor, but may be extended farther if this is desired. Tubular ventilators 50 are also provided in the corners of the top, as shown 40 in Figure 1, and these may be adjusted vertically through supporting sleeves 51 to bring their lower ends closer to or farther from the floor to regulate the ventilation as desired.

50 For the purpose of filling the boiler 10 with water, I have provided a basin 55 that is supported at the upper end of a vertical pipe 56 which connects, at its lower end, with the base of the boiler; the basin being disposed 55 substantially above the level of the boiler so that water poured therein will flow down the pipe 56 into the boiler. A drainage pipe 57 is also provided and this connects with the

lower end of the pipe 56 and, at its outer end, has a valve 58 which may be opened when it 60 is desired to drain the boiler. The water within the boiler is heated to generate steam or to provide hot water for heat, by means of an electric heating element 60, that is contained within the base of the boiler, as shown 65 in Figure 3, and this is electrically connected with a source of electricity by means of wires 61 and 62, and a thermostat 63 is connected in the circuit, being disposed within the brooder and operating automatically to control the circuit so that an even heat may be maintained within the brooder.

70 Mounted on the floor 40 about the base of the heater 10 is a wire screen wall 70 for preventing the chicks bunching or pressing too closely together against one another or against the tank and thus becoming overheated to their injury.

75 The screen, as shown, is circular in form but may be star shaped or have extending wings to break up the flock into smaller units.

80 It is understood that I do not limit myself to the specific construction set forth which may be varied within the scope of the claims.

85 Having thus described my invention, what I claim as new therein and desire to secure by Letters Patent, is:

1. In a brooder of the character described, 90 a floor, a boiler located centrally above the floor for containing a heating fluid, a pipe coil connected at its ends with the lower and upper ends of the boiler and comprising sections that are located, respectively, below the floor and at a spaced distance above it and means for supporting the boiler at different elevations with respect to the coil sections.

95 2. A brooder of the character described comprising a horizontal floor, a boiler for a fluid heating medium located centrally above 100 the floor, a pipe coil connected at its ends by flexible connections to the lower and upper ends of the boiler and comprising an upper section that is spaced above the floor to form the frame structure of the brooder, and comprising a coil section that is located below the floor, side walls and a top cover for the brooder supported on the upper coil, means 105 for controlling the circulation of the heating fluid through the coils and means for supporting the boiler at different elevations with respect to the coils.

110 Signed at Everett, Washington, this 16 day of March, 1927.

CHARLES I. NELSON.
